UNITED STATES PATENT OFFICE.

DAVID KUTNER, OF BROOKLYN, NEW YORK, ASSIGNOR TO ANNA M. KUTNER, OF SAME PLACE, AND LOUIS KAUFMAN, OF NEW YORK, N. Y.

FINGER-RING.

SPECIFICATION forming part of Letters Patent No. 394,928, dated December 18, 1888.

Application filed May 17, 1888. Serial No. 274,155. (No model.)

To all whom it may concern:

Be it known that I, DAVID KUTNER, of Brooklyn, in the county of Kings and State of New York, have invented a new and Improved Finger-Ring, of which the following is a full, clear, and exact description.

My invention relates to a setting for finger-rings and other jewelry; and the invention consists, principally, in small screw-clamps for holding the setting in the gem-box.

The invention also consists of the construction, arrangement, and combination of parts, all as hereinafter described.

Reference is to be had to the accompanying drawings, forming a part of this specification, in which similar letters of reference indicate corresponding parts in all the figures.

Figure 1 is a plan view of a finger-ring, showing my invention. Fig. 2 is a sectional elevation of the same, and Fig. 3 shows one of the screw-clamps.

A represents the gem-box, formed by the flange B. At each side the flange B is formed with the small screw-taps a to receive the screw-threaded shanks c of the screw-clamps C, which hold the gem or setting D in the gem-box, as shown clearly in the drawings.

The heads c' of the clamps C are made narrower in one direction and of considerable length in the other, so that when turned, as shown in Fig. 1, the elongated portion overlaps the setting or gem D and clamps the same firmly in place in the gem-box.

By turning the screw-clamps one-quarter around the setting of gem may be removed and another put in place and held by simply turning the screw-clamps.

My invention is applicable to brooches, lockets, sleeve-buttons, and other jewelry.

Having thus described my invention, what I claim as new, and desire to secure by Letters Patent, is—

A ring formed with the gem-box A and surrounding flange B, having screw-sockets a, in combination with screw-clamps C, having heads c', made narrow in one direction and of considerable length in the opposite direction to overlap the edges of the gem D and permit its removal from the gem-box, substantially as described.

DAVID KUTNER.
